Attorney.

UNITED STATES PATENT OFFICE

PHILIP NORTON ROSEBY, OF LIVERPOOL, ENGLAND, ASSIGNEE TO AUTOMATIC TELEPHONE MANUFACTURING COMPANY LIMITED, OF LIVERPOOL, ENGLAND

THERMO-MAGNETICALLY OPERATED DEVICE

Application filed April 26, 1928, Serial No. 273,134, and in Great Britain May 16, 1927.

The present invention is concerned with thermo-magnetically operated devices, that is to say devices in which motion is obtained by employment of the known principle that a magnetized member changes its magnetic properties under the influence of heat. Such devices may take the form of a motor adapted to have continuous motion in the same direction, or a relay which will move through a comparatively small distance, or, also, an arrangement which will move backwards and forwards with an oscillatory motion.

In one form of the invention constructed as a motor to operate continuously in the same direction, a ring of suitable magnetic material is pivoted so as to be free to revolve in its own plane and is arranged so that a portion of its circumference is in a magnetic field which may be provided either by a permanent magnet or by an electro-magnet. A suitable source of heat is applied to the ring close to the magnet so as to affect a portion of the ring lying within the magnetic field. As this portion of the ring becomes heated, its magnetic properties are modified and, in general, it will tend to lose its magnetism. Consequently the ring is subject to the action of two unequal magnetic forces acting in opposite directions and accordingly the resultant force causes the ring to revolve. As the hot portion of the ring moves away from the vicinity of the heater it will cool and will then regain its magnetic properties; consequently a continuous motion of the ring is obtained as long as there is a sufficient difference of temperature between the portions of the ring in the magnetic field. It is clearly necessary that the ring shall have cooled sufficiently to regain its magnetic properties by the time it again reaches the magnet for the rotation to be continuous, and this sets a limit to the speed of rotation, though cooling can be facilitated by suitably designing the containing chamber.

It will be seen that a construction similar to this can be employed for closing electric contacts, so that an electrical circuit may be closed or opened either when the source of heat becomes operative or, also, if an electromagnet is employed for providing the

magnetic field, when this is energized. Similarly by the use of two coils, one on each side of the magnet, controlled by contacts closed by the ring at each extremity of its travel, it may be made to move backwards and forwards in an oscillatory manner. Alternatively a restoring spring could be used, in which case only a single coil would be necessary.

The ring itself is preferably composed of nickel-iron wire with a composition of 63% iron and 37% nickel, the alloy being annealed at a temperature of 800° C. Pure nickel however may be used or, indeed, any magnetic material which loses its magnetic properties under the influence of heat and regains them unimpaired on cooling.

The pyro-magnetic arrangement according to the invention is particularly suitable for driving flicker-producing devices as used in imitation fires adapted to simulate the appearance of a burning coal fire, and such an arrangement will now be described by way of example, reference being had to the accompanying drawing wherein the single figure is a perspective view of the same. In said drawing, A is a sheet or disc of glass of substantially saucer shape having an irregular surface and pivoted at its centre with its convex side upwards. The glass A carries a non-magnetic frame F to which is attached a continuous tape or wire E of the nickel-iron alloy, constituting the previously-mentioned ring. Adjacent to the ring in one position is a heating element B which is preferably of spiral formation and is fitted to a grooved porcelain former which is then filled in with cement to prevent the element from moving. D is a permanent magnet, preferably of cobalt steel, having one of its poles adjacent to the heater and the ring. G is an electric lamp which forms the source of light, and suitable electrical connections to the lamp and the heater are made by way of the terminals C. The whole is supported on a brass frame H so that it forms a compact unit which may be readily fixed in position in imitation fires. As a matter of convenience the heating element and the electric lamp are run in series and they are so chosen that the heater will

produce the desired effect when working at a dull red heat, by which means its life is prolonged.

The action of the device will be readily understood from what has already been said, but it may be traced through briefly. When the current is switched on, the heater B comes into operation and heats the portion of the ring close to it so that this portion becomes non-magnetic. Hence the magnetic forces exerted by the magnet on the ring become unbalanced owing to the fact that a portion of the ring in the magnetic field is magnetic, while another portion is non-magnetic. Accordingly, a component is produced which serves to rotate the glass A. As soon as the heated portion of the ring moves out of range of the heater B, it commences to cool, and before it again comes into the magnetic field it has fully regained its magnetic properties. In consequence, a continuous rotation of the glass A is produced as long as the heater is in circuit. The light from the lamp G shining through the rotating glass A produces a flicker effect which is very realistic and is almost entirely free from the periodic or mechanical effect so often found in devices of this nature.

It will be understood that the invention is not limited to the arrangement in which the rotating glass is saucer-shaped; if desired, a complete cylinder of glass having an irregular surface could be employed or, alternatively, a flat glass plate carrying a cylindrical skirt of opaque material might be made use of. A still further modification, which would however introduce some additional complication, would be the provision of two concentric glass cylinders arranged to rotate in the same direction at different speeds or possibly also in opposite directions. It is found that the above driving arrangement, while being simple and reasonably robust, provides ample power for rotating a comparatively heavy piece of glass and has also the additional advantage that it will work equally well with either alternating or direct current.

What I claim as new and desire to secure by Letters Patent is:

1. For use in an imitation fire, a flicker-producing device comprising a source of light, a circular disc of glass having an irregular surface, said disc directly overlying said light source to be struck by the light rays emitted thereby, mounting means for supporting said disc while permitting it to rotate in its own plane, a ring attached to the disc, said ring being made of magnetic material which loses its magnetic properties on being heated, means for producing a magnetic field around a portion of said ring, and means for heating said ring in one portion of said field whereby the heated portion is rendered nonmagnetic and said ring and disc are ro-

tated by the action of said field on said unheated portion of said ring.

2. For use in an imitation fire, a flicker-producing device comprising a source of light, a saucer-shaped piece of glass having an irregular surface, said disc directly overlying said light source to be struck by the light rays emitted thereby, a pivot for rotatably mounting said glass with its convex side upwards, a continuous ring of nickel-iron alloy containing 30-40% of nickel attached to the circumference of said glass, a permanent magnet supported with one of its poles adjacent to a portion of said ring, an electric resistance coil located in the field of said magnet and adjacent to said ring, and means for supplying current to said coil whereby the portion of said ring adjacent to said coil is heated sufficiently to lose its magnetic properties and said glass is rotated due to the attraction between said magnet and the portion of said ring corresponding to said heated portion but located on the side of said magnet remote from said coil.

3. For use in an imitation fire, a flicker-producing device comprising a source of light, a piece of glass having an irregular surface, said glass overlying said source of light to be struck by the light rays emitted therefrom, means for mounting the glass for rotary movement to produce a flicker effect, and a pyro-magnetic motor for rotating said glass, said motor including a metallic ring member attached to the periphery of said glass, and fixed means arranged to cooperate with said metallic member to move the same and thereby effect the movement of said glass.

In testimony whereof I have signed my name at Liverpool, England, this 13th day of April, 1928.

PHILIP NORTON ROSEBY.
